Inventor

UNITED STATES PATENT OFFICE.

FREDERICK F. BENNETT, OF YPSILANTI, MICHIGAN.

WICK BURNER.

Application filed July 23, 1923. Serial No. 653,265.

To all whom it may concern:

Be it known that I, FREDERICK F. BENNETT, a citizen of the United States of America, residing at Ypsilanti, in the county of 5 Washtenaw and State of Michigan, have invented certain new and useful Improvements in Wick Burners, of which the following is a specification, reference being had therein to the accompanying drawings.

10 The invention relates to oil burners of the wick type and consists in certain improvements in construction whereby the wick is readily accessible and may be more easily adjusted and removed than in the usual 15 types. The features of construction and the advantages to be obtained therefrom are fully set forth hereinafter and illustrated in the accompanying drawings, wherein:—

Figure 1 is a sectional elevation of the 20 burner;

Figure 2 is a plan view thereof;

Figure 3 is a plan view of the adjusting handle;

Figure 4 is a longitudinal section through 25 the adjusting mechanism.

The improved burner comprises an outer cylindrical casing A having a raised bottom plate B and a central tubular member C, all suitably secured together to make an 30 annular oil chamber A' with an inlet connection A² communicating therewith near the bottom member B. The latter has an annular recess B' near the outer wall A and the adjacent annular shoulders B² forming one 35 wall of said recess. D is a cylindrical tubular member arranged coaxially with the outer casing A to form the annular wick chamber E therebetween. The cylinder D is held in position within the casing by having 40 the lower end inserted in the recess B' and engaging the annular shoulders B². F is a cover member having the annular flange F' closely fitting the walls of the tubular member D and secured thereto by suitable means 45 such as by indenting the metal of one member into the other. For clamping the member D in position there is a stud G' secured to the central tube C by a bracket G² and extending through an aperture F² in the 50 cover member where it engages the wing nut G.

H is an annular wick arranged in the annular chamber E between the outer casing and the cylindrical member D. The 55 wick is supported by a metallic sleeve I provided with a series of perforations J ar-

ranged in helical lines around the periphery thereof.

For raising and lowering the wick there is the toothed wheel K mounted upon a shaft L 60 journaled in the housing L' on the outer periphery of the casing A. The shaft L is obliquely arranged so that the teeth of the wheel K which project within the outer casing through a slot L² engage the sleeve I in 65 the apertures J. At the outer end of the shaft L is a knob M for actuating the wheel K to raise and lower the wick. It will be noted that because of the helical arrangement of the perforations J the wick is given 70 both a rotary and longitudinal movement by turning the knob. A lever N is rotatively mounted upon the shaft L adjacent to the knob M and is provided with inturned edges N' adapted to engage ratchet teeth M' peripherally arranged upon the inturned flange M² of the knob. The lever is resiliently held in engagement with the ratchet 75 by a spring O sleeved upon the shaft and abutting the shoulders O' while the inner 80 end of the lever is inwardly bent at N² to bear against the under surface M² of the knob. A bracket P mounted upon the tubular housing L' for the shaft L extends within 85 the annular flange M² of the knob and forms a fixed stop cooperating with the lever N to 90 limit the adjustment of the wick H.

With the arrangement as described, the lever N may be set in the required position 95 to limit the upward movement of the wick thereby insuring the proper regulation of the burner while, if it is desired to remove the wick, the lever is manually operable against the action of the spring O to release the teeth N' from the ratchet notches M' to 95 permit a full upward movement. Also, by removing the thumb nut G, the member D forming the inner guide for the wick may be easily removed thereby aiding greatly in assembly and disassembly of the wick. The member D, however, is positively secured 100 within the casing and is properly aligned therewith by the annular shoulders B².

In assembling the wick in the burner it 105 is placed in the annular chamber E so that the perforations J are aligned with the teeth of the wheel K and the knob M is turned counter clockwise causing a downward movement thereof. Because of the arrangement of the ratchet teeth M' it is unnecessary to manipulate the lever N for when the latter engages the fixed stop P it simply 110

rides over the teeth until the lower end of the sleeve I reaches the bottom of the recess B'. The length of the wick is preferably such that at this point it is entirely within 5 the annular chamber E but by turning the knob in the reverse direction until the lever again engages the fixed stop it is sufficiently raised to be lighted. This arrangement permits of easy assembly of the wick by a person not familiar with burner construction 10 since it is only necessary to turn the knob as far as it will go in one direction and then turn it as far as it will go in the other direction when the burner will be in condition 15 for use.

What I claim as my invention is:—

1. In a wick burner, the combination of an outer casing, an annular wick within said casing, and an inner guide for said wick 20 removably clamped to said casing.

2. In a wick burner, the combination of an outer cylindrical casing, an inner cylindrical member coaxially arranged within said burner casing and forming an annular 25 chamber therebetween, and means for removably clamping said inner member in fixed relation to said casing.

3. In a wick burner, the combination of an outer cylindrical casing, an inner member 30 arranged within said casing and forming an annular chamber therebetween, means for positioning said inner member coaxially with said casing, and means for removably clamping said member to said casing.

4. In a wick burner, the combination of an outer cylindrical casing, an inner member 40 arranged within said casing and forming an annular chamber therebetween, means for positioning said inner member coaxially with said casing, and means for removably clamping said member to said casing.

4. In a wick burner, the combination of a cylindrical container having a bottom provided with an annular recess forming adjacent annular shoulders, an inner cylindrical tube removably engaging said bottom in said 45 recess and positioned coaxially with said casing by said shoulders to form an annular chamber in said chamber, a fluid inlet for said chamber, and means for clamping said inner tube to said bottom.

5. In a wick burner, the combination with a container having spaced outer and inner walls, and a bottom connecting said walls provided with an annular recess forming 50 adjacent annular shoulders, of a tubular cylindrical member removably engaging said bottom and positioned coaxially with said casing by said shoulders to form an annular chamber, means for clamping said tubular member to said body, a fluid inlet for said annular chamber, an annular wick in said chamber, and means for raising and lowering said wick.

6. In a wick burner, the combination with 60 an oil container having a wick therein, of means for raising and lowering said wick including a rotatable shaft, a knob secured to said shaft, a fixed stop, a cooperating stop member normally engaging said knob to limit the movement of said wick, and manu-

ally operable means for releasing said co-operating stop member from said knob to permit the removal of said wick.

7. In a wick burner, the combination with an oil container having a wick therein, of means for raising and lowering said wick including a rotatable shaft, a knob secured to said shaft having teeth thereon, a lever rotatably mounted on said shaft and provided with teeth for engaging the teeth on said knob, a fixed stop engageable with said lever to limit the rotation of said knob, and a spring normally holding the teeth of said lever in engagement with the teeth of said knob.

8. In a wick burner, the combination of an outer casing, an annular wick therein, an inner tubular guide for said wick removably secured to said casing, a sleeve secured to said wick and provided with a series of apertures, a toothed wheel rotatably mounted on said casing and engaging said sleeve in said apertures, an operating knob connected to said wheel, an adjustable stop normally having a ratchet engagement with said knob, a fixed stop cooperating with said adjustable stop to limit the movement of said wick in one direction, the ratchet engagement of said adjustable stop permitting unlimited movement of said wick in the opposite direction, and manually operable means for releasing said adjustable stop from said knob to permit removal of the wick.

9. In a wick burner, the combination of a container having spaced cylindrical outer and inner walls forming an annular chamber therebetween, one of said cylindrical walls being removable, an annular wick longitudinally adjustable in said annular chamber and guided by said walls, and means for clamping said removal cylindrical wall in position to form said chamber.

10. In a wick burner, the combination with an oil container having a wick therein, of means for raising and lowering said wick including a rotatable shaft, a knob secured to said shaft having peripherally arranged ratchet teeth, a stop member rotatably mounted on said shaft and resiliently engaging said ratchet teeth, and a cooperating fixed stop member arranged to limit the movement of said knob in the direction to raise said wick while permitting unlimited movement in the opposite direction to lower the wick.

11. In a wick burner, the combination with a casing and a wick therein, of means for adjusting said wick comprising a rotatable knob for actuating said wick, an adjustable stop yieldingly held in a ratchet engagement therewith, a fixed stop cooperating with said adjustable stop to limit the movement of said wick in one direction, and means for normally releasing said ratchet

engagement to permit removal of the wick, said ratchet engagement permitting the actuation of said wick in the opposite direction without the release thereof.

- 5 12. In a wick burner, the combination with an oil container having a wick therein, of means for raising and lowering said wick including a rotatable shaft, a knob secured to said shaft having peripherally arranged 10 ratchet teeth, an adjustable stop member rotatably mounted on said shaft and resiliently engaging said ratchet teeth, a housing in which said rotatable shaft is journaled, a fixed stop secured to said housing and projected into the path of said adjustable stop member thereby cooperating with the same to normally limit the upward movement of 15 said wick while permitting unlimited movement in the opposite direction to lower said wick, said lever having its outer end projecting beyond the notches in said knob to form a handle for manually releasing said lever from said ratchet teeth to allow removal of the wick.

- 20 25 13. In a wick burner, the combination

with a container having spaced inner and outer cylindrical walls forming an annular oil-receiving chamber, of a tubular guide member removably insertable within said annular chamber and spaced from said outer 30 wall to form an annular wick chamber, and means for clamping said tubular member to said container.

14. In a wick burner, the combination with a container having spaced inner and outer cylindrical walls forming an annular oil-receiving chamber, of a tubular guide member removably insertable within said annular chamber and spaced from said outer 35 wall to form an annular wick chamber, said 40 container being provided with annular shoulders for positioning said tubular guide member, a cover member secured to the upper portion of said tubular member, and means for clamping said cover member to 45 said container.

In testimony whereof I affix my signature.

FREDERICK F. BENNETT.
